ELECTRIC REDUCER.

Application filed April 8, 1927. Serial No. 182,110.

Our present invention relates to certain improvements in electric reducers, its main object being to provide a new type of electric reducer consisting of a resistance which may be advantageously used in combination with any electric devices and particularly in combination with radio-receivers, the latter which with the use of our reducer operating perfectly with ordinary house currents of 10 220 volts or with other voltages.

In order that our invention be clearly understood and easily carried into practice, an embodiment thereof has been illustrated by way of example in the accompanying 15 drawing wherein,

Figure 1 is a front view of the resistance;

Figure 2 is a front view of a board having a double selective key which allows regulation at different voltages;

Figure 3 is a vertical cross-section showing the resistance connected to the board;

Figure 4 is a diagram showing the connection of the resistance to the board and the wiring and

Figure 5 is an embodiment of the reducer according to our present invention as specially adapted to be used in connection with electric bells.

Similar characters of reference denote 30 same or like parts throughout the said figures.

The resistance according to our present invention consists of a mixture in suitable proportions of smoke-black, vegetal coal and sugar syrup.

The mixture is prepared as follows: Smoke black such as lump black or soot and vegetal coal such as vegetable charcoal, peat, coal or lignite previously ground to powder are mixed together in suitable proportions according to the degree of resistance which may be required. Sugar syrup is then added in suitable quantities to form an homogeneous paste, which is then molded under slight pressure to give it the form shown in

Figure 1. Separate cylinders may also be formed and may be connected together by means of metallic connections. Suitable terminals or screws are embedded at the ends of the resistance element in order to effect

the necessary connections; and at the points where resistance is to be marked, copper wires are also embedded, said wires having a suitable length in order to reach to the contacts or taps to which they are to be connected.

The resistance is then covered with a suit-

able sheath of thin linen and is finally dried in a suitable stove.

As stated above, the proportions of the mixture may vary, but very good results have been obtained with a mixture of one part of smoke-black and two parts of vegetal coal, with a sufficient amount of sugar syrup to form the paste.

With a resistance element 1 as above, the controller or rheostat is prepared as follows: 65 The resistance element 1, suitably embedded in a base 2 of asbestos or the like, is lodged within a rectangular case 3. From the resistance 1, emerge the wires 4, and at its ends there are the terminals 5 which may be replaced by wires or the like. The front of the said box may consist of a panel 6 on which the contact arms or keys 7, and 8, are placed, said arms being independent of and insulated from each other. On the same panels are 70 also mounted the contacts or taps 9 which coact with the arm 7, and the taps 10 which coact with the arm 8. The contacts are connected two-and-two by means of copper wires as shown. The wires 4, are individually connected to the contacts 9 and 10. The electric current of 220 volts for instance enters through one of the terminals 5 of the resistance 1, the other terminal 5 being connected to the arms 7 and 8;

In the case of a resistance unit for electric bells as shown in Figure 5, the contact arms are eliminated and the unit is connected, according to the desired voltage, through the terminals or binding posts 11.

The resistance unit according to our present invention works as follows: For radio-receivers it has a panel with two or more contact arms if necessary, in order to obtain different intensities. The negative pole, or 90 the ground connection in the case of alternating current, is connected to one of the terminals and the current passes through the resistance element. From the arms 7 and 8, according to the tap 9 or 10 on which they 95 may be placed, two different voltages are obtained which advantageously substitute the two different intensities of the cells and batteries as used heretofore.

For other uses, where a successive regulation of the voltage is required, a single arm is used, said arm successively engaging the taps.

When using the reducer according to our present invention in combination with elec-

110

tric bells, two or more voltages are calculated, same being noted on the terminals 11 and the operator has simply to connect the outflow of the current with the terminal correspond-

5 ing to the voltage desired.

It is obvious that several modifications may be introduced without departing from the scope of our present invention which has been clearly set forth in the appended claiming

10 clauses.

Having now fully described and ascertained the nature of our present invention and in what manner the same is to be car-

ried into practice, we declare that what we claim and desire to protect by Letters Patent is:

An electric resistance comprising a mixture of smoke black, vegetal coal, and sugar syrup; and a linen covering surrounding said mixture.

In testimony whereof we affix our signatures.

JUAN FIDALGO.
FRANKLIN ORIVE.
FRANCISCO SANSÓ.
